UNITED STATES PATENT OFFICE.

CHARLES CHRISTOPHER MENGEL, OF LOUISVILLE, KENTUCKY, ASSIGNOR TO THE MENGEL COMPANY, OF LOUISVILLE, KENTUCKY, A CORPORATION OF NEW JERSEY.

BOX OR CONTAINER AND METHOD OF SEALING SAME.

Application filed July 9, 1919. Serial No. 309,624.

To all whom it may concern:

Be it known that I, CHARLES C. MENGEL, a citizen of the United States, residing at Louisville, in the county of Jefferson and 5 State of Kentucky, have invented certain new and useful Improvements in Boxes or Containers and Method of Sealing Same, of which the following is a specification.

This invention pertains to containers and 10 method of sealing the same, and has to do more particularly with boxes or containers made of fiber board or the like, which boxes or containers have come into extensive use of late years in displacement of wooden 15 boxes.

It is essential in the use of such fiber board containers that some adequate method of sealing the same be employed and the sealing should be effective against pilfering. 20 The method of sealing, moreover, must be such that it can be readily effected in the factory where the boxes are filled, and it must be such that the sealing or stitching, as the case may be, may be readily effected 25 when the box is filled, and this without damage to the contents of the box. To this end I have devised a box or container wherein openings or slots are formed in oppositely disposed portions of the box structure 30 through which a thin anvil may be extended, the anvil underlying the box flaps or closures and permitting proper functioning of the stitching mechanism.

The box which forms the basis of the invention is shown in the accompanying drawings, wherein,—

Fig. 1 is a perspective view of the upper portion of the box or container made in accordance with my invention;

Fig. 2 a similar view showing the end flaps, having the slots formed therein, partially turned down with the anvil threaded therethrough;

Fig. 3 a longitudinal sectional view of the upper portion of the box showing the anvil in place and the various flaps or closures turned and stitched;

Fig. 4 a transverse sectional view on the line IV—IV of Fig. 3;

Fig. 5 a perspective view of the closed and stitched box;

Fig. 6 a perspective view of the upper portion of the box showing the flaps as provided with a plurality of openings;

Fig. 7 a perspective view of the top of

such a box when the flaps have been turned down and stitched;

Fig. 8 a perspective view of the upper portion of the box showing a further arrangement of the slots.

Referring first to Figs. 1 to 5 inclusive, 1 denotes the body of the box, 2 and 3 the end flaps, respectively, and 4 and 5 the side flaps. The end flaps 2 and 3 will each be provided with a slot or opening, as 6, adjacent the line of bend or hinge connection of the flap with the box body. To stitch the box thus formed, I project through the openings 6, a thin flat anvil 7, shown in Figs. 2, 3 and 4. Said anvil will overlie the goods within the

box and after it is positioned, as shown in Fig. 2, the side flaps 4 and 5 will be turned inwardly and a suitable stitching mechanism brought into operation to effect the stitching, as indicated in Figs. 3 and 4. 70 Such stitching mechanism may take any of the commercial forms but preferably will be designed to drive U-shaped wire staples, as 8, the ends of which when they are driven inwardly through the overlapping flaps will 75 abut the anvil 7 and be clinched thereby.

As will be readily appreciated upon inspection of the drawings, not only will the flaps 4 and 5 which overlap be thereby secured to one another but the staples will pass through 80 the flaps 2 and 3 thereby securing the underlying flaps 2 and 3 to the uppermost flaps 4 and 5. The anvil will preferably be supported close to the box so as to prevent undue bending thereof under the impact of 85 the stitching mechanism and thus breakage of the material within the box will be prevented. So, too, crushing of the walls of the box will likewise be prevented.

Owing to the fact that the flaps 2 and 3 are attached by the staples to the overlying flaps 4 and 5, the package becomes pilfer proof as one can not by prying the attached flaps 4 and 5 upwardly, force the flap 2 or 3, as the case may be, inwardly and pass 95 their hand into the container. Thus the container is made pilfer proof and if it is opened by forcing the staples, it will be readily seen that such action has taken place. By forming the slots 6 in the flaps 100 the slots are covered over by the uppermost or side flaps and when the box is withdrawn from the anvil, said slots are substantially if not entirely hidden.

It is conceivable that a plurality of alined

slots may be formed in the opposite flaps, and in Fig. 6 the end flaps are shown with a series of slots, three in number, and a box so formed and stitched is shown in Fig. 7 with three rows of stitches.

In Fig. 8 the side flaps are shown as provided with two slots which, of course, would effect the sealing of the box and enable a shorter anvil to be used.

10 The arrangement is such that by the use of the thin anvil there is practically no bulging of the flaps and no breaking down of the box structure, points of manifest advantage.

15 What is claimed is,—

1. That method of sealing a box or container having closure flaps adapted to be inturned upon each other to close the box, which consists in passing an anvil through openings formed in oppositely disposed flaps, turning said flaps down, thereafter turning the remaining box flaps thereover and finally stitching the flaps together by suitable fastenings driven through the flaps 25 and against the anvil.

2. That method of sealing a box or container having closure flaps adapted to be inturned upon each other to close the box, which consists in passing an anvil through 30 openings in oppositely disposed end flaps, said openings being located adjacent the line of connection of the flap to the box body, turning said flaps down upon the anvil, then turning the side flaps over upon the end flaps, and finally stitching the flaps together by suitable fastenings driven through the 35 superposed flaps and against the anvil.

3. That method of sealing a filled box or 40 container having a closure flap connected to each side wall of the box, which consists in inserting an anvil through openings formed in two oppositely disposed flaps, said anvil being coextensive at least in length with

that of the box, infolding said flaps upon the anvil, then infolding the remaining flaps, stitching the overlying flaps together by fastenings driven through the flaps and against the anvil, and finally withdrawing the anvil.

4. As a new article of manufacture, a box 50 or container comprising a body having a plurality of closure flaps adapted to be infolded to close the box, two of said flaps at least having oppositely disposed slots or openings formed therein, said slots being 55 located respectively in proximity to the line of bend or hinge of the flap.

5. As a new article of manufacture, a box 60 or container comprising a body having a plurality of closure flaps adapted to be in-turned to close the box, with an opening 65 formed in two oppositely disposed flaps, said openings being located, respectively, adjacent the line of bend or hinge of the flaps to the box body.

6. As a new article of manufacture, a box 70 or container having a body rectangular in cross section with a closure flap formed at each side as a continuation thereof, two of the oppositely disposed flaps each having a 75 slot or opening formed therein adjacent the line of bend between the flap and the body.

7. As a new article of manufacture, a box 80 or container having a body rectangular in cross section with a closure flap formed at each side as a continuation thereof, two of the oppositely disposed flaps each having a slot or opening formed therein adjacent the line of bend between the flap and the body, the remaining pair of flaps being of such size as when folded down to cover the underlying flaps and to overlap each other.

In testimony whereof I have signed my name to this specification.

CHARLES CHRISTOPHER MENGEL.
